UNITED STATES PATENT OFFICE

2,334,313

ELECTRIC SWITCH

John R. Caldwell and William A. Gussow, Birmingham, Ala., assignors to Southern States Equipment Corporation, a corporation of Alabama

Application March 9, 1942, Serial No. 433,854

7 Claims. (Cl. 200—48)

This invention relates to switches of high ampere capacity, with small-area high-pressure contacts at each end of the swing arm. Some of the purposes are to provide a switch without any flexible conductors between movable members, a switch in which the flow of current is in a continuous straight line with the bus-bar conductors at each end, and a switch which has ample current carrying capacity at the joints and yet which can be opened and closed easily under all weather conditions. Other purposes will be evident from the specification and the claims. The method of operation is a modification of the system shown in the copending application Serial No. 331,496, filed by John R. Caldwell on April 25, 1940, now Patent No. 2,276,257, issued March 10, 1942.

The drawings show one design of switch in which our invention is embodied. Fig. 1 is a side view of a single pole unit, several of which may be used to form a multiple-pole switch. Fig. 2 shows in larger scale a side view of the operating members at the hinge end of the swing arm; Fig. 3 is similar to Fig. 1, but shows one switch unit in open position; Fig. 4 shows in larger scale the hinge side of the switch in open position; Fig. 5 shows a plan of the hinge and the arm members just after the opening motion has started; Fig. 6 shows in side view the jaws and the end of the switch arm as opening motion begins; Fig. 7 is a plan view of the members shown in Fig. 6; Fig. 8 shows a plan view of the swing arm similar to Figs. 5 and 7, but without showing the adjacent supporting and contact members; Figs. 9 and 10 show, respectively, the jaw and hinge contact members in plan view, without the swing arm; Fig. 11 shows in partial section the unit which gives the heavy-pressure spring action at the switch contacts. Fig. 2 shows the members in fully closed positions; Figs. 5, 6 and 7 show the members just as opening motions have started, with the links 24 and 40 in vertical position and the contact projections 31, 32, 36 and 37 just released from the two pairs of spaced contacts 14 and 35.

A base 1 supports two stationary insulators 2, 3 and a rotative insulator unit 4 to which is connected the crank 5 for operating insulator 4 and for interconnection with other similar units to form a multipole switch. At 6 and 7 connections are made between the main line conductors and the switch terminals. The bearing 8 supports the rotative insulator unit, to which is secured the crank 9, which holds one end of the connecting bar 10. The side bars 11, 11 and the pivot

12 carry the hinge-arm 13 of the main swing arm. A pair of spaced contacts 14, 14 are fixed to the bars 11, 11, which are partly supported by the pressure unit 15 while still having a limited lateral flexibility. The bars 11, 11 are held by the bearing which supports crank 9, and at 6 they are also held by the main line bus bars 16. The hinge-arm 13 carries the pivots 17 and 18. Pivot 17 supports the clevised operating-link 19 whose upper end is pivotally connected by pin 19' to the rocker 20 whose lower end is pivoted to the top of insulator 2 by pin 21. Operating-link 19 carries pins 22 and 23; pivot 18 carries links 24, 24 with pins 25 and 26; pins 22 and 25

5 carry the reciprocating contact 27 to which are secured the bars 28, 28 which form the outside members of the switch swing arm. Pins 23 and 26 carry the reciprocating contact 29 to which are secured the bars 30, 30 forming the inner members of the switch swing arm. Projections 31, 31 on reciprocating contact 27 touch the two spaced contacts 14, 14 so that 27 bridges the spaced contacts 14, 14. In a similar way reciprocating contact 29 through its projections 32, 32

15 carries the same spaced contacts 14, 14. Thus two small-area contacts are made against each of the spaced contacts 14, 14.

The jaw contacts of the switch are similar and the various members function in a similar way. Bars 33, 33 are supported by arm 34. Spaced contacts 35, 35 are integral with bars 33, 33 and they are engageable by projections 36, 36 and 37, 37 on reciprocating contacts 38 and 39, respectively. Reciprocating contact 38 is terminal for bars 28, 28, and reciprocating contact 39 terminates bars 30, 30. Links 40 and pivots 41, 41 movably connect reciprocating contacts 38 and 39. If the swing arm, as shown in Figures 4 and 8, is considered without reference to other members, it will be seen that if the hinge-arm 13 remains stationary while the operating-link 19 is rocked back and forth about its pivot 17, the pins 22 and 23 will move the reciprocating contacts 27 and 29 in opposite directions and this will cause the two sets of contact projections, 31—32, 31—32 and 36—37, 36—37, alternately to approach one another and then to separate. And simultaneously the projections 36, 36 and 37, 37 on reciprocating contacts 38 and 39, respectively, 25 alternately approach one another and then separate.

The pressure unit 15 is shown in Figure 11. The base 42 is pivoted at 43 and carries two inwardly facing cups 44, 44 in each of which is a spring 45 which presses the pin 46 towards the

bar 11. Pin 46 fits movably into a recess in the bar 11. The spring 45 has preferably initial compression from the screws 47, and a limited possible expansion; and the bars 11, 11 preferably have a slight outward bias, so that the pins 46 tend to remain in their recesses in bars 11, and yet the bars 11 under heavy pressure can expand slightly and thereby compress the springs 45, without causing permanent distortion to any members. Screws 48 provide means for adjustment. Unit 15' is similar to unit 15.

Operation is as follows:

Figure 2 shows the members in closed position. Rotation of insulator 4 causes rod 10 to pull arm 20 in counter-clockwise rotation, and pin 19' follows the arc A, which is inscribed about the center 21, to position marked 19'B. While 19' travels through the space C the center-lines 21-19' and 17-19' are close together and the arc DD, which is inscribed about the center 17, substantially coincides with the arc A; and so the operating-link 19 is merely rotated about its pivot 17, while the main switch swing arm remains stationary.

While the operating-link 19 is moving over space C in a counter-clockwise direction from the fully closed position, the pins 22 and 23 move reciprocating contacts 27 and 29 in opposite directions, making projections 31 and 32 move simultaneously away from spaced contacts 14, 14. At the same time and in a similar way spaced contacts 35, 35 are released from the contact pressure exerted upon them by projections 36, 36 and 37, 37. Further travel of pivot 19' from space C towards position 19'B exerts an upward pressure, through operating-link 19 and pivot 17, upon the hinge-arm 13, which is thereby raised until the whole switch swing arm reaches the fully open position shown in Figures 3 and 4. Thus the entire switch swing arm is moved as a unit around pivot 12 from closed to open position. This swing arm includes members 13, 21, 28, 29, 30, 36, 37, 38 and 39.

Conversely, when the switch is being closed the swing arm comes down to horizontal position by the time pin 19' reaches the space C. Reciprocating contacts 27 and 29 are between spaced contacts 14, 14 and reciprocating contacts 38 and 39 are between spaced contacts 35, 35. Further travel of pin 19' over space C forces projections 31, 31 and 32, 32 towards one another, bringing the projections against the bevelled surfaces of spaced contacts 14, 14. Travel is short and the leverage is great, so that when all members are properly proportioned there is a heavy wedging effect exerted by the projections against the spaced contacts 14, 14, which are thereby spread slightly against the pressure of the springs 45. Thus four small-area high pressure wiping contacts are established and pressures of several hundred pounds are developed between the separable current carrying areas. At the same time the projections 36, 36 and 37, 37 similarly engage spaced contacts 35, 35 and spread the bars 33, 33 slightly against the springs in unit 15', developing four similar high pressure contacts at the jaw end of the switch.

The high pressures thus made are developed by the pins 22 and 23 which force each pair of reciprocating contacts, 27-29 and 38-39, towards one another. The links 24 and 40 guide and coordinate the two movable portions of the switch swing arm but do not either increase or decrease the contact pressures. As the pressure is applied to or released from the two pairs of spaced contacts 14, 14 and 35, 35, these contacts

spread outwardly or draw inwardly but they do not move longitudinally of the switch arm, for all necessary longitudinal motion is made by the reciprocating contacts and the projections upon them.

The switch may be mounted in any position and suitable balancing springs may be provided, if desired, to balance the weight of the switch swing arm. Sleet covers may be added to protect the various movable members if this should be wanted; and various adjustments are provided for convenience in assembling the switch.

If desired, the double spring contacts may be replaced by rigid contacts each of which is clamped upon opposite sides by the two reciprocating contact members of the swing arm, without causing any wiping action. Also other additions or modifications may readily be made by one familiar with the art, without departing from the purpose and spirit of this invention.

We claim:

1. In an electric switch, two spaced insulated supports, a relatively stationary pair of spaced contacts mounted upon one of said supports, a swing arm pivotally mounted upon the second of said supports and movable into and out of contact with the said spaced contacts to operate the switch; the said swing arm including a reciprocating contact movable longitudinally of the swing arm to bridge the said spaced contacts, and a second reciprocating contact movable simultaneously but in the opposite direction to bridge the same spaced contacts.

2. In an electric switch, two spaced insulated supports, a relatively stationary pair of spaced contacts mounted upon the first of said supports, a swing arm mounted about an axis on the second of said supports and movable into and out of engagement with the said spaced contacts to operate the switch; the said swing arm including a reciprocating contact movable longitudinally of the swing arm to bridge the said spaced contacts, a second reciprocating contact movable simultaneously but in the opposite direction to bridge the same spaced contacts, a simultaneously operable second pair of reciprocating contacts adjacent the said axis; together with a second pair of spaced contacts mounted upon the said second support and cooperable with the said second pair of reciprocating contacts.

3. In an electric switch, two spaced insulated supports, a relatively stationary forked pair of contacts mounted upon the first of said supports, a swing arm mounted upon the second of said supports and movable into and out of contact with the said forked contacts to operate the switch; the said swing arm including a reciprocating contact movable longitudinally of the swing arm to engage both of the said forked contacts and wedge them apart, and a second reciprocating contact movable simultaneously in the opposite direction to engage the same said forked contacts and wedge them apart.

4. In an electric switch, two spaced insulated supports, a relatively stationary pair of spaced contacts mounted upon the first of said supports, a swing arm mounted about an axis on the second of said supports and movable into and out of engagement with the said spaced contacts to operate the switch; the said swing arm including a reciprocating contact movable longitudinally of the swing arm and having on each side a projection to engage one member of the said spaced contacts, and a second reciprocating contact movable simultaneously but in the opposite direc-

tion to engage directly and to bridge the same spaced contacts.

5. In an electric switch, two spaced insulated supports, a relatively stationary contact member mounted upon one support, a hinge-arm swingably mounted about a stationary axis upon the other support and carrying a pair of reciprocating contacts which are both conductively engageable with the said contact member, an operating-link pivotally mounted on the hinge-arm and pivotally connected with the said two reciprocating contacts to move them in opposite directions; together with a rocker pivotally mounted upon the said other support on a stationary pivot remote from the said stationary axis, a pivot connecting the said rocker and the said operating-link, and means to move the rocker to operate the switch.

6. In an electric switch, a relatively stationary contact, an insulated support spaced from the said contact, a swing arm structure mounted about a stationary axis upon the said support and movable into and out of engagement with the said stationary contact; the said swing arm structure including a pair of reciprocating contacts cooperable with the said stationary contact, an operating link, two spaced pivots connecting the said reciprocating contacts with the said operating-link, a third pivot intermediate the said two spaced pivots for movably mounting

the said operating-link upon the swing arm structure; together with a rocker mounted upon the said support on a stationary pivot remote from the said axis, a pivot connecting the said rocker with the said operating-link, and means to move the rocker to operate the switch.

7. In an electric switch, two spaced insulated supports, a relatively stationary pair of spaced contacts mounted upon one of said supports, a swing arm pivotally mounted upon the second of said supports and movable into and out of contact with the said spaced contacts to operate the switch; the said swing arm including a reciprocating contact movable longitudinally of the swing arm to bridge the said spaced contacts, and a second reciprocating contact movable simultaneously but in the opposite direction to bridge the same spaced contacts, an operating-link pivotally mounted upon the hinge-arm and pivotally connected with the two said reciprocating contacts to move them in opposite directions; together with a rocker pivotally mounted upon the said second support on a stationary pivot remote from the said stationary axis, a pivot connecting the said rocker and the said operating-link, and means to move the rocker to operate the switch.

JOHN R. CALDWELL.
WILLIAM A. GUSSOW.
